UNITED STATES PATENT OFFICE.

GEORGE HIGLEY, OF CLEVELAND, OHIO, ASSIGNOR TO THE CLEVELAND HARDWARE COMPANY, OF CLEVELAND, OHIO, A CORPORATION OF OHIO.

FRAME-SECTION OF VEHICLE RUNNING-GEAR.

No. 911,240.

Specification of Letters Patent.

Patented Feb. 2, 1909.

Application filed July 13, 1906. Serial No. 326,087.

To all whom it may concern:

Be it known that I, GEORGE HIGLEY, a citizen of the United States, residing at Cleveland, in the county of Cuyahoga and 5 State of Ohio, have invented a certain new and useful Improvement in Frame-Sections of Vehicle Running-Gear, of which the following is a full, clear, and exact description.

The object of the invention is to provide a 10 strong and durable frame section for vehicle running gears; and said invention is an improvement upon the construction which forms the subject matter of my pending application No. 316,068, filed May 10, 1906.

15 In the drawing, Figure 1 is a perspective view, partly broken away, of a metallic frame section embodying the present invention. Fig. 2 is a side view, partly broken away, of the engaging ends of one 20 of the reach irons and the member to be embraced by and secured to the same,—this figure being for the purpose of showing how said two parts are put together. Fig. 3 is a side view of the same parts after they are 25 fastened together; and Fig. 4 is a transverse sectional view, either on line X or line Y of Fig. 1.

The frame includes a head block plate A having two integral rearwardly extending 30 arms a, the two reach irons B, and the two reach heels C. The reach irons are made of thin metal and of inverted U-shape in transverse section. The front ends of these 35 reach irons are cut off diagonally, inclining forward from the top down. The rear ends of these irons are of similar shape, except that they incline rearwardly from the top down.

The rear ends a' of each of the arms A is 40 reduced in diameter and is of such size and shape that it fits snugly within the front end of one of the reach irons. The rearwardly faced shoulder a² between the arm a and its reduced end a' is inclined forward from its 45 top toward its bottom,—the line of said inclination corresponding with the inclination of the front end of the corresponding reach iron. On top of the reduced end a' is a rivet pin a³ which may be integral with the reduced end of the arm a or may be 50 permanently secured thereto. In the top of the reach iron is a hole b through which this rivet pin may be passed. These two parts are assembled by putting them in the relative 55 position shown in Fig. 2, and then swing-

ing the part B downward until the rivet pin a' passes through the hole b. At this time the inclined shoulder a² and the inclined front end of the reach iron will abut and engage with each other and will be firmly held in 60 this position when the upper end of the rivet pin is upset, as shown in Fig. 3. These two parts b and a' will preferably be brazed together, but the described construction and connection, including the inclined shoulder 65 a², and inclined front end of the reach iron, together with the rivet pin a³ hold the parts firmly together, prevent all possibility of rattling and make a very strong and durable connection. The reach heels C are similarly 70 provided with a forwardly extended reduced portion c',—there being between said reduced portion and the main body of said heel a rearwardly faced inclined shoulder c which corresponds in shape and inclination 75 with the rear end of the reach iron. A rivet pin c² is rigid with the reduced portion c' of the reach heel, and it passes through a hole in the reach iron and when upset firmly fastens said reach iron and reach heel to- 80 together. As in the case of the connection between the front end of the reach iron and the arm a, the reach heel is preferably additionally secured to the reach iron by 85 brazing them together.

Having described my invention, I claim:

1. In a frame section for a vehicle running gear, the combination of a reach iron made of thin metal of substantially the shape of an inverted U in cross section, and having 90 its end beveled forward from top to bottom, and having a hole through its top side, with a piece having a beveled shoulder which fits the beveled end of said reach iron, and having a reduced end which is fitted into the end 95 of the reach iron, and a rivet pin which projects from said reduced end through the hole in the reach iron and is upset thereon.

2. In a frame section for a vehicle running gear, the combination of a head block plate 100 having two rearwardly projecting arms, each of which has a rearwardly faced inclined shoulder, and, behind that, a reduced end which fits into the end of the reach iron and has an upwardly projecting rivet pin, with 105 two reach irons each made of thin metal of inverted U-shape in cross section which is fitted upon the reduced part of one of said arms, and has its front end beveled to fit against said shoulder and has a hole through 110

which said rivet pin passes,—said rivet pin being upset upon said reach irons.

3. In a frame section for a vehicle running gear, the combination of two reach irons made of thin metal of substantially the shape of an inverted U in cross section, and having their ends beveled in opposite directions, and having holes through their tops near said ends, combined with a head block plate 5 having two rearwardly extended arms each having a rearwardly faced inclined shoulder and a reduced end which fits into the end of one of said reach irons and has an upwardly extended rivet pin which passes 10 through the hole in said reach iron and is 15

upset thereon, and two reach heels each of which has a forwardly faced inclined shoulder and forwardly extended reduced portions which are fitted into the rear ends of said reach irons, and an upwardly extended rivet 20 pin which passes through a hole in said reach iron and is upset thereon.

In testimony whereof, I hereunto affix my signature in the presence of two witnesses.

GEORGE HIGLEY.
